To all whom it may concern:

Be it known that we, EDWARD C. DENNIS and ROBERT M. SHIPLEY, citizens of the United States, residing at Wichita, in the county of Sedgwick and State of Kansas, have invented a new, original and ornamental Design for an Emblem, Badge, Ring, Stickpin, Brooch, Watch-Charms, Lapel-Button, or other Article of Similar Nature, of which the following is a specification, reference being made to the accompanying drawing, forming part thereof.

In the drawing:

Figure 1 is a plan view of a lapel button showing our new design, and,

Fig. 2 is an edge view thereof.

We claim:

The ornamental design for an emblem, badge, ring, stickpin, brooch, watch-charm, lapel button or other article of similar nature as shown.

EDWARD C. DENNIS.
ROBERT M. SHIPLEY.
